UNITED STATES PATENT OFFICE.

JAMES HENRY BLOODGOOD, OF JACKSONVILLE, FLORIDA, ASSIGNOR TO THOMAS H. SPENCER, TRUSTEE, OF BIRMINGHAM, ALABAMA.

PORTABLE HAND-PLANER.

1,296,911.

Specification of Letters Patent. Patented Mar. 11, 1919.

Application filed July 23, 1918. Serial No. 246,399.

To all whom it may concern:

Be it known that I, JAMES H. BLOODGOOD, a citizen of the United States, and a resident of Jacksonville, in the county of Duval 5 and State of Florida, have invented certain new and useful Improvements in Portable Hand-Planers, of which the following is a full, clear, and exact description.

The present invention relates to a portable hand tool, more particularly portable hand planers, to be used in smoothing exposed surfaces of wooden and other structures and also adapted, dependent upon the character of cutter, to performing the operation of roughing timbers, or to form a furrow or channel, or to prepare the seams in the deck flooring or the sides of wooden ships preliminary to the operation of calking.

20 The object of the present invention is to produce such a portable tool of simple and strong construction, and to provide therein for the effective clearance of the waste produced in the operation of the tool in order that the same shall not become clogged in operation.

25 A further object is to provide a construction by means of which, and by a simple form of adjusting mechanism, the depth of cut may be quickly regulated and adjusted.

30 A further object of the invention is to provide such a tool which can be quickly arranged so that the effective operation of the cutters may take place on surfaces 35 closely adjacent to other parts of the structure operated on, as in the angles between the deck floor and the upstanding sides of the ship.

35 A further object of the invention is to 40 provide for the effective lubrication of the operative parts and to permit the power driving connections to be changed from one side of the tool to the other, all as will be hereinafter set forth.

45 To the above ends, the present invention 50 consists of a hand planer comprising a body portion with a pivoted tool carrier arranged to be adjusted with relation to the body portion to cause the working face of the tool to be projected varying distances beyond the face of the body portion. It further consists of the devices and combination of devices which will be hereinafter described and claimed.

The invention is shown in the accompanying drawing which:

Figure 1 shows a perspective view of the device.

Fig. 2 shows a longitudinal sectional view taken on a vertical line cutting the longitudinal center of the device.

Fig. 3 shows a transverse vertical sectional view taken on the line 3—3 in Fig. 2 looking in the direction of the arrow on such line.

Fig. 4 shows a transverse sectional view taken on the line 4—4 in Fig. 2 looking in the direction of the arrow on line 4—4.

Fig. 5 shows a side elevation of the tool with the forepart of the body portion removed so as to permit working close in angular corners.

Fig. 6 shows one of the bushings of the shaft bearings removed.

Similar reference characters will be employed throughout the specification and drawings to designate the corresponding parts.

As shown in the drawings, the tool is equipped with a saw "1" which is angularly disposed on its shaft as shown in Figs. 3 and 4, commonly known as a "wabble saw", arranged to cut a groove "2" in the surface being treated. It is to be understood however, that in place of the "wabble saw" "1", may be substituted a planing cutter, a roughing off cutter, or a plowing cutter, or any other desired tool, the operating face of which is arranged to perform its work by a rotary motion.

The main frame or body portion comprises two sections, "3" and "4", each of which consists of a face plate "5" and "6", provided along their opposite longitudinal edges with the vertical upstanding parallel sides "7" and "8" respectively; the sides "7" being carried by the section "3", and the sides "8" by the section "4". The sides "7" at their forward upper ends are united by a cross plate or brace "9". The section "3" also carries a suitable grip or handle "10" and the section "4" a suitable grip or handle "11". These sections "3" and "4" as so far described, may each of them be formed of a single casting of any suitable light, but strong metal, or if desired, the grips or handles "10" and "11" may be separately formed and secured to their respective mem-

bers in any suitable or convenient manner. The section "4" is removably connected to the section "3", and for this purpose the section "3" or the side walls thereof "7", at 5 their forward ends are provided with rabbeted recesses "12" into which the ends of the side walls "8" of the section "4" are adapted to fit, and in which they are secured by means of screws "13" arranged to 10 be received in threaded openings "14" in the side walls "7" of the section "3".

In ordinary use the tool is employed as shown in Fig. 1, but when it is desired to work close upon a surface closely adjacent 15 to a vertical surface, the forward section "4" is detached, thus producing the effect as shown in Fig. 5, which brings the cutting tool close to the forward end of the section 3.

The upstanding walls of the sections provide a box-like frame, which is open from 20 end to end longitudinally, and in this opening is arranged the tool carrier "15", which consists of an open frame having parallel side members "16" and a top member "17", 25 all formed preferably of an integral casting of some suitable, but light and strong metal, and near the lower edges and near the forward end the tool carrier "15" is provided with a crossbar "18" to brace the side walls 30 thereof. The tool carrier "15" is pivotally supported at its rear end upon a shaft "19" whereby it may have an up and down movement for purposes which will be hereinafter described. The tool carrier "15" is provided 35 with suitable bearings "20" which are threaded into seats or sockets "21" in the walls thereof, and in which is supported for rotary movement the tool carrying shaft "22" upon which is mounted the cutter, or 40 other tool "1", held fixedly thereto by any suitable means, as by means of the threaded nut "23", engaging a threaded portion "24" of the shaft "22" and the coöperating bushings "25" and splines "26". Any suitable 45 means may be adopted for rigidly affixing the tool to the shaft. The side walls "7" of section "3" of the body portion are cut out upon segmental lines as shown at "27", to permit the bearings or bushings to have 50 freedom of movement therein and also to assist in permitting the escape of the waste produced by the tool. For this purpose also, a large clearance space "28" is provided in the body portion to prevent clogging of the 55 tool. The pivotal action of the tool carrier "15" is intended to provide for the vertical adjustment of the cutting edge of the tool with relation to the bottom or face plate of the body portion, so as to provide for regulating the depth of the cut, and in the apparatus as shown there is a considerable 60 latitude of vertical adjustment controlled and operated by a single adjusting device.

This adjusting mechanism consists of a 65 threaded screw "29" engaging a threaded

aperture in the crossbar "9". At its lower end it is provided with a swivel "30" to which is pivotally connected a link "31", which at its lower end is connected to the cross-brace or bar "18". The arrangement 70 is such that by turning the screw "29" the pivotal tool carrier "15" may be raised or lowered about the shaft "19" as a center, thus raising or lowering the tool, and at the same time rigidly holding the tool in its 75 adjusted position. The shaft "22" is driven from any suitable source or power by means of a flexible shaft "32" which is arranged to have a detachable connection, as by means of a screw thread "33", with the shaft "22". 80 Of course, this connection may be at either side of the device. As shown in the drawing, it is on the left hand side, but by removing the shaft "22" and transposing the bearings "20", the connection may be placed 85 at the right hand side.

For the purposes of lubrication the side walls "7" immediately over the bearings for the shaft "22", are provided with oil-ducts "34" leading into the bearings for the shaft, 90 and oil-cups "35" provided with caps "36" are mounted on the tool carrier immediately over the oil-ducts "34".

Within the bearings "20" I provide tubular bushings "37" which are cut out as shown 95 at "38" to receive a packing "39". These bushings are made of light ductile metal and provide effective means for retaining lubrication at the points of bearing the shaft "22".

It is to be noted that the top "17" of the tool carrier is cut out or provided with a notch "40" at its forward end to permit clearance of the adjusting devices therefor, and that the milled head "41" of the adjusting screw "29" has a rounded upper surface 105 permitting its use as a knob or handle when the forepart of the device is removed, as shown in Fig. 5.

It is desirable at times when working 110 upon a surface close to another surface at right angles thereto, to permit the tool to work close to the angle, and for this purpose the forepart of the tool is made removable, as has been explained.

It is thought that the operation of the device has been sufficiently set forth in connection with the foregoing description of its construction and that further description of the operation thereof is unnecessary.

Having described my invention I claim as new and desire to protect by Letters Patent of the United States:

1. In a portable power driven hand planer, in combination, a main frame including side 125 walls and a base plate having an opening intermediate its ends, said frame open from its front to its rear end, a tool carrier pivotally supported at its rear end in the main frame adjacent its rear end and provided 130

- with a power driven tool operating through the opening in the base plate, said tool being reversible in said frame, and an adjusting device connecting the front end of the 5 pivoted tool carrier to the main frame, whereby to adjust the tool through the opening relatively to the base plate and to hold the tool rigidly in its adjusted position.
2. In a portable power driven hand planer, 10 in combination, a main frame comprising separable front and rear sections having base plates and side walls, the base plates spaced from each other, a rotary power driven tool mounted in the rear section and projectable 15 down past and in front of its base plate, and means for detachably connecting the front section of the main frame to the rear section, the detachable connection being closely adjacent to the point of operation of the tool.
- 20 3. In a portable power driven hand planer, in combination, a main frame comprising separable front and rear sections having base plates, the base plate of the rear section terminating short of the front end of said section and providing an opening, and a cross bar or brace above said opening, a power driven tool pivotally mounted in the rear section and operating through the aforesaid opening, and means for detachably connecting the sections at a point immediately in 25 front of the power driven tool.
4. In a portable power driven hand planer, in combination, a main frame including side walls and a base plate having an opening therethrough, said frame open from end to end, an adjustable tool carrier open from end to end pivotally mounted at its rear end within the main frame providing a free clearance space at the rear of said frame and 30 a power driven cutter carried by said tool carrier and arranged transversely therein.
- 40 5. In a portable power driven hand planer, in combination, a main frame composed of two sections, the forward section detachably connected to the rear section, a handle carried by each of the sections, a power driven cutter carried by the rear section and operating through the base thereof, an adjusting device for said cutter located near the forward end of the rear section, said adjusting device having a rounded head whereby it may serve as a handle when the forward section is removed.
6. In a portable power driven hand planer, 45 in combination, a main frame open from end to end and including side walls having downwardly and rearwardly inclined open slots, a tool carrier pivotally mounted at its rear end between the side walls, and carrying a rotary power driven shaft at its forward end, said shaft projecting through the aforesaid slots in the side walls of the rear section and adjustable therein and removable entirely therefrom through the open end of the slots without detaching the pivot- 50 ed tool carrier from the main frame, and an adjusting device for said tool carrier adjacent the forward end of the frame.
7. In a portable power driven hand planer, 55 in combination, a main frame composed of front and rear sections and having an opening through its base, said sections separably connected, a tool carrier pivotally mounted at its rear end within the rear section, and carrying a power driven rotary tool shaft 60 at its front end, and adjustable means for the forward end of the tool carrier, said means including a screw engaging the main frame, a link pivotally connected at one end to the forward end of the tool carrier, and 65 swiveled at its other end to the aforesaid screw, said screw also serving as a handle when the forward section is removed.

JAMES HENRY BLOODGOOD.
